UNITED STATES PATENT OFFICE.

LEON WISLOCKI, OF NEW YORK, N. Y.

WINDOW LOCK.

Application filed December 27, 1924. Serial No. 758,339.

To all whom it may concern:

Be it known that I, LEON WISLOCKI, a citizen of Poland, residing at New York city, in the county of New York and State 5 of New York, have invented certain new and useful Improvements in Window Locks, of which the following is a specification.

This invention relates generally to window locks, having more particular reference 10 to a window lock arranged for application to the window at the time it is desired to lock the latter and which is capable of ready application to and removal from the window.

The invention has for an object the provision of a simple and novel lock of this sort which operates by causing the window sash to bind or wedge against the frame if an attempt is made to open the window when the lock is applied to the latter. 15 For further comprehension of the invention, and of the objects and advantages thereof, reference will be had to the following description and accompanying drawing, and to the appended claims in which the 20 various novel features of the invention are more particularly set forth.

Fig. 1 of the drawing is a perspective view showing my improved lock applied to a window.

Fig. 2 is a vertical sectional view showing the lock in position on the window, the lock being shown in elevation, this view being taken on the line 2—2 of Fig. 3.

Fig. 3 is a horizontal sectional view taken 35 on the line 3—3 of Fig. 2.

Fig. 4 is a detail perspective view of the lock.

Fig. 5 is a face view of the blank from which the lock is formed.

Fig. 6 is a similar view to Fig. 2 but showing a modified construction of lock.

In constructing my improved window lock I form a sheet metal blank such as is shown generally at 10 in Fig. 5 of the drawing, 45 which tapers from end to end thereof as shown, and has the pairs of teeth or spikes 11 and 12 projecting from the sides and front thereof respectively. This blank is bent, along the dotted lines 14 shown in 50 Fig. 5, to the form shown in Fig. 4 to comprise a central elongated body member 10' and the side flanges or walls 10^a which extend at right angles to the said central mem-

ber. It will be noted that the lines 14 start from the narrow end of the blank at the corners of the latter, and diverge slightly from one another toward the other end of the blank, the divergence of the lines 14 being less, however, than that of the two sides of the blank from one another. The result is 55 that when the blank is bent as above described the flanges 10^a decrease in depth from one end of the lock to the other, while the lock tapers from the first mentioned end toward the other end. A wedge element 60 which tapers both of its face and sides is 65 thus formed.

In applying my improved lock to a window the lock is engaged with one of the sash retaining strips 16 of the window above the 70 sash 17, being retained in position by the engagement of the spikes 11 and 12 in the said strip. If an attempt is made to open the window the sash bears on the face of the lock and is thereby forced laterally to bind 75 or wedge at its opposite side against the adjacent side of the window frame.

In the form of the device shown in Fig. 6 of the drawing the lock is constructed in the main as above with the body member 10', 80 side flanges such as 10^a, and spikes 11 and 12. In this case the central member 10' is extended at the entering or narrow end of the lock in the form of a hook 20 which engages in an undercut recess 21 in the sash, 85 the top wall of this recess being here formed by a plate 22 fixed to the top of the sash. Attached at one end to this plate is a flat spring 23 which extends upwardly therefrom, and bears on the body of the lock, 90 causing the spikes 11, 12 to be pressed lightly against the frame strip 16. With this arrangement the window can be readily locked in partially open position without forcing the spikes into the strip 16. If, in 95 a clandestine attempt to open the window, the sash 17 be first pulled downward, the lock will follow the sash and reengage when a new attempt is made to raise the sash. As will be apparent, the lock may be readily removed from the sash by swinging it on the corner of the latter the spring 23 yielding to permit of this action. Replacement of the lock is effected in like manner.

Having thus described my invention, what 105 I claim as new and desire to protect by Let-

ters Patent of the United States is as follows:—

A window lock comprising a wedge element, side flanges formed with said element, 5 spikes or spurs formed with said flanges adapted to engage the window frame, a hook extension formed with the lower end of said element adapted to engage an undercut re-

cess in the window sash, and a spring bearing on said lock for causing said spikes to enter the window frame upon an attempt to open the window. 10

In testimony whereof I have affixed my signature.

LEON WISLOCKI.
